UNITED STATES PATENT OFFICE.

JOHN F. DONOVAN, OF PHILLIPS, WISCONSIN.

STACK-ROOF.

SPECIFICATION forming part of Letters Patent No. 633,689, dated September 26, 1899.

Application filed June 2, 1899. Serial No. 719,080. (No model.)

To all whom it may concern:

Be it known that I, JOHN F. DONOVAN, a citizen of the United States, and a resident of Phillips, in the county of Price and State of Wisconsin, have invented certain new and useful Improvements in Stack-Roofs; and I do hereby declare that the following is a full, clear, and exact description thereof.

My invention has especial reference to devices for protecting stacks of hay, straw, or grain from rain or snow; and it consists in certain peculiarities of construction and combination of parts, as will be fully set forth hereinafter and subsequently claimed.

In the drawings, Figure 1 is a representation of a stack of hay, straw, or grain protected by my device, the roof-boards being shown in section. Fig. 2 is an inner side elevation showing two of the separable roof-boards and their connecting attachments.

Referring to the drawings, A represents in outline a stack of hay, straw, or grain, and B B the separable roof-boards, there being also two boards (marked C C) which are united together at an angle to form the top of the roof, from which top the remainder of the boards are suspended, as shown. Each of the separable roof-boards B is provided, near each end thereof and on the inner or under side, with a connecting-strap D, said straps being preferably formed of strips of flat metal bent at an angle, as shown at b, near their upper ends, so as to form an offsetted upper end c, which latter is further provided with a transverse slot d, and the lower ends of said straps are bent outwardly to form heels e for better support of the boards B, to which said straps D are secured, as by nails or screws f f. Near its lower end each strap D is punched to form an inwardly-projecting bent catch or lip g for engagement with the slot d in the strap of the adjacent board.

The united top boards C C are provided on the under side and near each end thereof with a doubled strap E, the lower ends of which are formed with heels e and lips g, corresponding to those of the individual straps D.

In applying a roof to a stack the top C is first placed upon the apex of the stack, and then the two upper boards B B are suspended

therefrom, as shown in Fig. 1, by hooking the slotted upper ends of the straps on said boards to the lips g g on the doubled straps E, the upper edges of said boards B B being beneath 55 the lower edges of the top boards C C, as shown, and then other boards B B are similarly attached to and beneath the lower edges of the uppermost of the separable boards B B, and so on, using as many of said separable 60 boards B B as the size of the stack requires, ordinarily only the sloping upper part of a stack requiring such protection. The lowest pair of boards B B may be held to place in any suitable manner—as, for instance, by 65 means of cords, ropes, or chains F F, secured to the lips g g of the straps D D on said boards, and heavy weights G G at the lower ends of said cords, ropes, or chains—and it is 70 obvious that the latter may be fastened to stakes driven in the ground, if desired, as indicated by dotted lines in Fig. 1, to aid in keeping the roof upon the stack. Inasmuch as all the boards are provided with the described connecting-straps all in line with each 75 other at each end it will be apparent that a stack can be very quickly roofed over with my devices and the said roof as readily removed when desired, without the necessity of any change in or addition to the same or the use 80 of any tools or nails and that the said device can be used season after season without alteration and will occupy very little space in storage when not in use.

Having thus described my invention, what 85 I claim as new, and desire to secure by Letters Patent, is—

1. In a stack-roof, the combination with an angular top piece provided with doubled straps transversely secured to the under side 90 and adjacent to each end thereof, the lower ends of said doubled straps being bent upward to form heels, in engagement with the lower edges of said angular top piece, of a series of separable or removable boards, each 95 having straps secured transversely to the under side and adjacent to each end thereof, said straps being bent upward at each end to engage with the upper and lower edges of said board, and the upper end of each strap 100 projecting in line with, and flush with the upper surface of, said board, and provided

with a perforation, and each strap having a downward-extending and upward-projecting lip intermediate of its ends.

2. In a stack-roof, the combination of a series of separable or removable roof-boards, each having straps secured transversely to the under side and adjacent to each end thereof, said straps being bent upward at each end to engage with the upper and lower edges of 10 said board, and the upper end of each strap projecting in line with, and flush with the upper surface of, said board, and provided with a perforation, and each strap having a downward-extending and upward-projecting 15 lip intermediate of its ends.

3. A strap for attachment to the roof-boards of a stack-roof consisting of a flat metallic plate bent upward at each end, the upper end extending beyond the line of said bend and having a perforation therethrough, and there 20 being an integral lip punched from said strap intermediate of its ends.

In testimony that I claim the foregoing I have hereunto set my hand, at Chicago, in the county of Cook and State of Illinois, in 25 the presence of two witnesses.

JOHN F. DONOVAN.
